UNITED STATES PATENT OFFICE

2,505,539

PRESSURE OPERATED SWITCH

John O. Gill, Barnesboro, Pa.

Application May 14, 1946, Serial No. 669,539

1 Claim. (Cl. 200—83)

1

This invention relates generally to signaling apparatus and pertains particularly to an improved apparatus for use in connection with mine ventilating systems.

The present invention has for its primary object to provide a signaling mechanism which is designed to be used in association with the ventilating fan or fans used in association with mine ventilating systems for the purpose of designating when the fans are operating at proper speed and for giving an audible warning signal in the event of the stoppage of the air circulating fan or in the event that its speed falls to a point where proper air movement is not being maintained.

Another object of the invention is to provide a signaling mechanism wherein is employed an oscillatable circuit controller which has two positions, in one of which positions a signal lamp is maintained energized during the operation of the ventilating fan at proper speed while in the other position such signal lamp is deenergized and a battery operated audible signal is energized to indicate the reduction of the fan's speed to a dangerous point.

Still another object of the invention is to provide a safety signaling apparatus of the character stated with the air circulating fan of which is operatively connected through a suitable speed reduction mechanism, a rocking switch which is closed once for each of a predetermined number of revolutions of the fan to intermittently energize an indicating light whereby a visual means is provided for indicating when the fan is running at constant speed and also for indicating any slowing up of the speed prior to the operation of the audible signal.

The invention will be best understood from a consideration of the following detailed description taken in connection with the accompanying drawings forming a part of the specification, with the understanding, however, that the invention is not confined to a strict conformity with the showing of the drawings but may be changed or modified so long as such changes or modification mark no material departure from the salient features of the invention as expressed in the appended claim.

In the drawings:

Figure 1 illustrates diagrammatically the circuit control units together with the electric circuits associated therewith, forming a part of the present invention.

Figure 2 is a view in elevation of the fluid pressure actuated switch controlling unit.

2

Figure 3 is a view in side elevation of the circuit control switch operated by the speed reduction mechanism.

Figure 4 is a front view of the structure shown in Figure 3.

Figure 5 is a side view of the fluid pressure operated switch controlling unit, portions of the structure being broken away to show details of construction.

10 Referring now more particularly to the drawings the numeral 10 generally designates a fluid pressure operated unit for controlling the oscillatable switch unit 11 by means of which certain hereinafter described electric circuits and signal 15 elements are energized under prescribed conditions.

The unit 10 comprises a two part housing or a casing in which the parts are designated 12 and between which is secured the flexible diaphragm 20 13.

To the lower section or half of the diaphragm enclosing body is connected a pipe line 14 which is in communication with the fan chamber or housing, not shown, of the ventilating system in 25 association with which the present invention is used. Fluctuations in the air pressure within such fan enclosing chamber operate to flex the diaphragm 13 and move the switch unit 11.

Mounted upon the top of the diaphragm unit 10 is the switch unit 11, as shown, and which 30 comprises a platform or plate 15 disposed between upstanding bearings 16 and pivotally connected therewith by pins 17 whereby the plate may be oscillated. At one side of the center of 35 oscillation for the plate 15, the plate has pivotally connected therewith an end of an actuating rod 18 which passes downwardly through the top portion 12 of the diaphragm housing and is attached to the diaphragm 13 as indicated at 19. Thus it 40 will be seen that when the diaphragm moves up or down corresponding movement will be given to the plate 15.

If desired the opposite ends of the plate 15 may be fitted with balance arms 20 upon each of 45 which may be shiftably supported the balance weight 21. By properly adjusting the weight upon the arms 20 the plate 15 may be delicately balanced if desired so as to react easily to movements of the diaphragm.

Supported upon the top of the plate 15 in holders or clips 22 is a mercury switch tube 23, in each end of which is fixed a pair of conductors whereby the mercury switch may control two separate circuits.

55 As shown in Figure 1 one pair of conductors 24

which enter one end of the mercury tube, controls the signal circuit 25 while in the opposite end of the mercury tube is connected the pair of conductors 26 which control the energization of the electric circuit 27. This circuit 27 is supplied with electric current from any suitable source which, for example, may be the source from which current is supplied for the operation of the ventilating system apparatus in association with which the herein disclosed safety apparatus is used and accordingly there are shown the leads 28 with which such supply source may be connected. Also in the circuit 27 is connected a signal light 29 which is energized when the mercury switch 23 is inclined so as to establish an electrical connection between the electrodes or terminals 26.

Since the present apparatus is designed to give a warning in the event that electrically operated apparatus ceases to function and especially if such cessation is due to the failure of the electric current supply it will be obvious that the signal circuit 25 must be independent of such current supply and accordingly this circuit 25 is shown as having connected therein a source of electric potential in the form of a battery 30. Also connected in the circuit 25 is a manual switch 31 and an audible signaling element 32 here shown as being in the form of a bell. It will be evident, however, that the audible signal 32 may comprise a horn, siren or any other mechanism for creating sound.

Also forming a part of the present signal system is a means for designating by the intermittent operation of a signal light, when the ventilating system fan is operating at proper speed. For this purpose there is provided a gear reduction unit which is generally designated 33 and which comprises a power input shaft 34 which is directly coupled with a ventilating fan to be rotated thereby, and a power output shaft 35 which, by reason of the gear reduction mechanism, is rotated at a greatly reduced speed from the shaft 34. For example, the reduction rate may be 50 to 1 or 100 to 1 so that the shaft 35 will be turned once or twice to every 100 revolutions of the ventilating fan motor.

The shaft 35 has connected therewith the crank 36 and this is connected by the link 37 with a crank pin 38 which is carried at one side of an oscillatable switch support or cradle 39. The switch support is pivotally mounted between suitable bearings 40 so that as the crank 36 rotates rocking movement will be given to the cradle as will be readily apparent.

Upon the top of the cradle 39 is secured between the clips 41, the mercury switch tube 42 into one end of which extends electrodes 43 which are connected in the signaling circuit 44. Also connected in the circuit 44 is a signal lamp 45 and the circuit is supplied from any suitable source by the necessary electric power which is connected with the leads 46.

It will be readily seen from the foregoing that the signaling circuit 44 will be intermittently energized by the oscillation of the mercury switch 42 and accordingly it will be readily apparent to anyone observing the signal light 45 when the fan

operating motor is performing properly. In the event of any difficulty which might make the operation of the ventilating fan motor erratic the signal light 45 will fail to light at properly timed intervals or will fail to light at all if the fan motor has ceased functioning. In the latter event the pressure diaphragm 13 will be affected and the audible signal will be sounded to give a warning if the condition of the fan has not been noted visually.

From the foregoing it will be readily apparent that when the present apparatus is installed in a mine ventilating system and properly connected with the electrically operated units thereof adequate warning will be given in the event that the air circulating apparatus fails for any reason to function properly and accordingly the necessary steps can be taken immediately to remedy the situation and thus avoid the possibility of some dangerous conditions developing.

I claim:

A fluid actuated diaphragm controlled electric circuit control comprising a housing having upper and lower portions between which a free moving diaphragm is secured, the top of the housing being open and a fluid pipe opening into the housing beneath the diaphragm, spaced upright supports mounted upon the upper portion of the housing, the opening in the housing top being between said supports, a platform disposed between the supports, pivot means connecting opposite side edges of the platform with the supports whereby the platform is oscillatably carried by the supports, a rod secured at one end to the diaphragm and extending upwardly through said opening and having pivotal connection at its other end with the platform, the connection between the rod and the platform being to one side of the pivot support for the platform whereby the movements of the diaphragm will effect oscillation of the platform, a pair of spaced clip members carried upon the platform, a mercury switch secured at its ends between the clip members to be maintained above and substantially in parallel relation with the top of the platform, and elements supported upon two opposite ends of the platform for regulating the balance thereof, comprising a long threaded arm extending longitudinally from each of such ends and a balance weight threaded on each arm.
